LINOLEUM OR SIMILAR ARTICLE

George W. Johnson, San Francisco, Calif., assignor to Pabco Products Inc., San Francisco, Calif., a corporation of Delaware

Application April 28, 1953, Serial No. 24,730

Term of patent 7 years

(Cl. D92—17)

To all whom it may concern:

Be it known that I, George W. Johnson, a citizen of the United States, residing in the city and county of San Francisco, State of California, have invented a new, original, and ornamental Design for Linoleum or Similar Article, of which the following is a specification, reference being had to the accompanying drawing, forming part thereof.

The drawing is a plan view of a piece of linoleum, showing my new design. On such drawing, the broken lines outline a design unit which is repeated in regular succession as indicated by the extensions beyond the boundaries of such unit.

I claim:

The ornamental design for linoleum or similar article, substantially as shown and described.
